UNITED STATES PATENT OFFICE.

MAURICE G. KLEMMIE, OF BELLEVILLE, ILLINOIS.

RANGE CONSTRUCTION.

Application filed January 27, 1928. Serial No. 249,832.

The object of my device is to make a range construction for the jointure of the walls of an oven and for the jointure of the walls with the front frame of an oven, which jointure will 5 obviate the necessity of the use of bolts or welding or other conventional means. Ovens of the type in consideration such as are used on gas ranges for domestic purposes are enamelled. When bolts or other conventional 10 means of jointure are used, stresses and strains are set up and produced in the metal adjacent the bolts or other securing means. When the metal is subject to differences in temperature due to the stresses and strains set 15 up around the bolts, the enamel cracks or becomes crazed. One of the objects of my invention is to prevent this cracking and crazing. A further object is to make the thermal 20 seal between the oven door and the oven frame more nearly perfect when the oven is closed than is customarily done with the conventional structure. A further object is to so devise the oven door and the frame in which it 25 fits so that the door and frame will be self centering.

With these and other objects in view, my invention has relation to certain novel features of construction and arrangement of parts as will be hereinafter more fully described, 30 pointed out in the claim and illustrated in the drawing in which,

Fig. 1 is a schematic front elevation of an oven frame with the oven door, the latter being in its closed position.

Fig. 2 is a fragmental sectional elevation on the line 2-2 of Fig. 1, and

Fig. 3 is a fragmental sectional plan view on the line 3-3 of Fig. 1.

Numeral 4 designates the oven generally to 40 which is hingedly secured the oven door 5 by means of the conventional hinges 6. Numeral 7 designates an angle iron door frame into which the oven door 5 is seated when the door is in its closed position. The door 5 does not 45 extend entirely from lead line of 5 in Fig. 3 to the inner wall 7 in the same figure. The angle iron door frame is formed of the shank 8 and the plate 9 formed at right angles and integral with the shank 8. Numeral 10 designates a small projection outwardly from the 50 plate 9 parallel to the plane of the shank 8.

Fig. 3 is a modification of Fig. 2, the door 5 extends entirely from 5 to 10 in Fig. 2. Numeral 11 designates the sheet metal top of the oven and numeral 12 the interior top wall of the oven. Numeral 13 designates one of the lateral walls of the oven and numeral 14 the interior lateral wall of the oven. My invention concerns itself principally with the jointure of the sheet metal top 11 to the angle iron door frame 7 and the sheet metal lateral wall 13 with the angle iron door frame 7. The sheet metal that is to form the top 11 and the interior top wall of the oven 12, as well as to encompass the angle iron door frame 7 is 60 stamped into the shape shown in Figs. 2 and 3 so that the sheet metal is bent over and around the shank 8, and the plate 9. When this single piece of sheet metal has been thus stamped and the angle iron door frame 7 is 65 in its operative position, it only becomes necessary to press or force the stamped sheet metal from the front rearwardly in a horizontal plane to bring it into the position indicated in Fig. 2. The fit between the 70 stamped sheet metal and the angle iron door frame is such that the frictional engagement between them sustains them in the relative position shown in Fig. 2 after having been initially placed in such a position. Before 75 the products of combustion can make their exit from the oven, they must pass between the surfaces of the door and the surfaces of the stamped sheet metal portion against which the door is supported.

In order to sustain the angle iron door frame 7 in its proper position, the following instrumentalities are employed. Numeral 16 designates a rod threaded at both ends. A hole is tapped and threaded in the plate 9. A similar hole is tapped in the rear portion of the frame of the oven so that the rod 16 may be secured in these holes by the threaded engagement between the ends of the rod and the holes. Lock nuts 17 are placed in threaded engagement on the ends of the rod 16 internally relative the plate 9 and the rear wall of the oven. By a tightening of the lock nut 17 the relative position of the angle iron door frame 7 and the rear wall of the oven is established. The same construction that has 85 been described herein for the jointure between 90 95 100

the top of the oven and the front frame element is employed for the jointure between the lateral walls of the oven and the front frame element.

5. What I claim and mean to secure by Letters Patent is:

In combination with an oven frame, a sheet

metal wall having its edges bent around the edges of said frame, a door, the sides of the door, conforming in shape with the edges of 10 the sheet metal wall with which the door is in contact in its closed position.

In testimony whereof I affix my signature.

MAURICE G. KLEMME.
